CLAIM

The ornamental design for a welding power supply roll cage with incorporated lift handles, as shown and described.

DESCRIPTION

FIG. 1 is a front right top perspective view of a welding power supply roll cage with incorporated lift handles showing our new design;

FIG. 2 is a front right bottom perspective view thereof;

FIG. 3 is a side elevation view thereof;

FIG. 4 is a front elevation view thereof;

FIG. 5 is a rear elevation view thereof;

FIG. 6 is a top plan view thereof; and,

FIG. 7 is a bottom plan view thereof.

In these drawings, the solid lines illustrate the claimed ornamental design, whereas the broken lines illustrate environmental features that form no part of the claimed ornamental design.
